UNITED STATES PATENT OFFICE.

ALBERT EDWARD SHINER, OF LONDON, ENGLAND.

ROTARY PUMP.

1,340,632.

Specification of Letters Patent. Patented May 18, 1920.

Application filed April 19, 1918. Serial No. 229,623.

To all whom it may concern:

Be it known that I, ALBERT EDWARD SHINER, a subject of the King of Great Britain, residing at London, England, have 5 invented new and useful Improvements in Rotary Pumps, of which the following is a specification.

This invention relates to rotary pumps of the kind having a pendulum rotor the stem 10 of which slides in an oscillatory member, the outlet for the fluid being through the stem of the rotor.

According to the present invention, particularly applicable to a pump having a short throw, the oscillating member in which the stem of the pendulum slides is made in one piece having a radial slot from end to end for receiving the pendulum stem, and a central outlet for the liquid or fluid 20 pumped.

A further improvement applicable to a pump for pumping air or other compressible fluid consists in so arranging the oscillating member in relation to the outlet passage in the stem of the pendulum that, when the pendulum is on the top dead center, it prevents the escape of fluid from the outlet end of the pump back to the inlet.

30 A still further improvement relates to providing the pendulum bob of a pump used for pumping liquids with tangential channels, adapted to throw the liquid against the wall of the pump chamber, or with pockets or cavities in its periphery to receive any solid matter that may pass into the pump, and thereby to make it more efficient in action.

Referring to the accompanying drawings, 40 which illustrate the invention,

Figure 1 is a view of the pump with one of the end plates removed to show the inner working parts.

Fig. 2 is a view looking from the right 45 of Fig. 1.

Fig. 3 is a central transverse section of the oscillating member in which the pendulum stem works.

Figs. 4 and 5 are side views of the pendulum bob showing different forms of channels in its periphery.

Fig. 6 is a section taken on the line α , α Fig. 7, and

Fig. 7 is a side view of a pendulum having recesses or pockets formed in the periphery of the bob.

Fig. 8 shows a modified construction which provides for locking the fluid when the pendulum is at the top dead center.

A is the pump chamber which is closed at the sides by plates C, D; G is the driving shaft; H the eccentric fixed on the driving shaft; J is the pendulum bob; K the stem of the pendulum; and Q the outlet channel formed in the stem K. S is a cylindrical oscillatory piece working in a cylindrical recess formed in an extension of the pump chamber.

The oscillatory piece S is slotted at s throughout its length to receive the stem 70 of the pendulum, and has an outlet orifice at t for the outlet of the liquid or fluid. P is the inlet to, and R the outlet from the pump casing. This pump will work in either direction, if desired.

In the periphery of the pendulum bob in pumps used for pumping liquids I provide a number of tangential channels W which extend across the cylindrical face of the bob either parallel to the axis, or in an 80 inclined direction as shown in Fig. 4, or said tangential channels may be double helical shaped as shown in Fig. 5. These tangential channels have the effect of throwing the liquid against the wall of the pump 85 chamber. In some cases in lieu of channels such as W, I provide in the periphery of the bob and arranged in any suitable formation a number of pockets or recesses M as shown in Figs. 6 and 7. These pockets 90 or recesses serve to collect any solid matter that may pass into the pump.

In the case of a pump for pumping air or other compressible fluid, I may arrange the oscillating member S closer to the pump 95 chamber as shown in Fig. 8, so that when the pendulum is at the top dead center, it closes the mouth of the channel Q in the stem K, and thus prevents the fluid from escaping back to the inlet side of the pump 100 while the pendulum is in this position.

What I claim is:—

A rotary pump comprising a pump-chamber, a pendulum rotor consisting of a bob and a stem, the latter having a delivery 105 channel passing longitudinally through it,

an oscillating member seated in an extension of the pump-chamber, said member being made in one piece slotted from end to end to receive the stem of the pendulum rotor, 5 and having a central outlet for the fluid, the periphery of the pendulum bob being provided with tangential channels for throwing

the liquid against the wall of the pump chamber.

ALBERT EDWARD SHINER.
